UNITED STATES PATENT OFFICE

DWIGHT D. KIMBALL, OF NEW YORK, AND VICTOR J. CUCCI, OF BROOKLYN, NEW YORK,
ASSIGNORS TO COLUMNAR HEAT, INCORPORATED, OF NEW YORK, N. Y., A COR-
PORATION OF NEW YORK

FLOOR FITTING

Application filed March 27, 1930, Serial No. 439,416. Renewed September 15, 1932.

This invention relates to floor fittings for heat exchange systems of buildings and has for its particular objects the provision of a combined anchorage and pipe joint fitting which is intended to be located at the different floor levels of a building and is adapted to not only hermetically unite adjacent riser sections together, but also to provide a sleeve member which serves both as a location means and as a liner for the opening through the floor. Our improved floor fitting which essentially constitutes a sleeve, anchor and joint fitting serves to provide a support, sleeve and anchor for the riser pipe and to materially simplify and reduce the labor cost in the installation of the heating system. Other advantages of our invention are hereinafter set forth.

Heretofore it has been customary to project a riser pipe through registered openings in the different floor levels and to apply to such pipe at certain floor levels only a supporting collar, each collar being adapted to rest on the top surface of a floor and serving to support the riser pipe, but these collars do not readily lend themselves to the convenient assembly of the riser pipe sections in their superimposed relation, besides failing to provide as effective a seal between the abutting ends of the riser pipe sections which were anchored therein as is desirable in steam heating systems. Our investigations have led to the discovery that these various objections can be effectively overcome by the improved construction hereinafter described.

In the accompanying drawing forming a part of this specification

Figure 1 is a fragmentary vertical section, partially in elevation of a building equipped with a heating installation embodying one form of our invention;

Fig. 2 is a fragmentary elevation, partially in vertical section, showing our improved anchorage flange and pipe fitting, isolated.

Referring to the drawing and the description shown therein, a riser section 7 is provided with a bottom terminal flange 10 which is adapted to co-operate with a similar flange 10' of an inverted riser section 7' that projects upwardly through the con-

crete flooring of a building and upon which the same is superimposed. A sleeve member 11 which, as previously stated, serves as a mold during the pouring of the concrete floor to form the aperture for the reception of the riser section, is provided with a bottom flange 12 and vertical ribs 13, said sleeve being of an inverted truncated cone configuration at its upper end as indicated by the reference numeral 14. Two apertured plates 15 and 16 respectively, which preferably are of generally triangular shape and each of which has a series of bolt-receiving apertures 17, 17' that are adapted to register with each other and to admit of the reception therethrough of bolts 18, serve to secure the opposing flanges 10, 10' of the pipe sections 7 and 7' together, this being accomplished by applying the nuts 19 to the upper end of the bolts and screwing the same home until the flanges 10, 10' are in intimate contact and the upper ends of lugs 20, which constitute flattened heads of said bolts, are in engagement with the lower face of the plate 16. Thereupon cap screws 21 mounted in the lugs 20 are turned down until the same engage and ride downwardly on the inclined face of the conical end 14 of the sleeve 11, which latter has been previously anchored in the concrete floor, and thereby the said pipe sections will be held in hermetically tight engagement with each other and anchored to the sleeve 11.

As shown, the plate members 15 and 16 are preferably of triangular shape and the so-called central aperture thereof is somewhat off center, whereby riser sections are permitted to hug quite closely the outer wall of the building, but obviously, if desired, circular discs or plates of other shapes could be employed and the central apertures therethrough likewise disposed somewhat off center.

In order to guide or align the lugs 20 so that they will present the cap screws carried thereby with their longitudinal axis substantially at right angles to the axis of the riser pipe section which it is desired that the lugs shall engage, we provide stop pins or lugs *a*, the same being formed integrally on

the lower face of the plate 16 and thereby lugs 20 will be prevented from turning as the nuts 19 are screwed home and as a consequence, the cap screws 21 will be held in a 5 properly alined position.

Among the various advantages possessed by our improved construction are its simplicity and cheapness, as well as the fact that our improved device forms a permanent 10 and hermetically tight joint.

While we have described and illustrated certain preferred embodiments of our invention in the specification and drawing of this application, we do not wish to be understood 15 as limiting our invention thereby as various changes therefrom may be made without departing from the spirit of the invention as embraced within the scope of the appended claims.

20 Having thus described our invention, what we claim and desire to obtain by United States Letters Patent is:—

1. An anchorage unit for a heat exchange system, comprising a sleeve member of inverted frusto-conical configuration at one end and having a terminal flange at its other end, a flanged riser pipe section extending through said sleeve, an opposing pipe section also having a terminal flange adapted to register 25 with the flange on the first mentioned pipe section, and means for sealing the joint between the flanges on said pipe section when the same are in assembled relation including a plurality of apertured plates respectively 30 encircling said pipe sections, a plurality of bolt members each having a terminal lug member, the shanks of said bolts being adapted to be inserted through the apertures of said plates, retaining nuts adapted to be threaded on the ends of said bolts, and transversely 35 extending adjusting means carried by said terminal lug members of said bolts and means for anchoring said sleeve in a concrete mass in which the same is embedded.

2. An anchorage unit for a heat exchange system, comprising a member having a terminal flange at one end, a riser pipe section having a terminal flange corresponding to the flange on said member and adapted when 40 brought into tight engagement therewith to form a fluid-tight joint therewith, a centrally apertured plate carried by said pipe section, the aperture in said plate being of substantially smaller diameter than the extreme diameter of the terminal flanges, a flanged sleeve of sufficient size to embrace said pipe section and being of inverted truncated cone-like configuration at one end and having a flange at its opposite end and bolt members 45 having a transversely extending adjusting means thereon for securing said flanges to said sleeve and forming a unitary anchorage.

3. An anchorage unit for a heat exchange system, comprising a sleeve member of variable cross section at one end, a plurality of

members having flanges, a plurality of plates each having a central aperture of smaller diameter than the extreme diameter of said flanges and each having peripherally disposed bolt-receiving apertures and one of said plates being adapted to be fitted over each of the aforesaid members, lug-carrying bolt members, each provided with adjusting screws, for securing said flanged members in fluid-tight engagement with each other and for anchoring the same to said sleeve. 70

4. An anchorage unit for a heat exchange system, comprising a sleeve member of inverted frusto-conical configuration at one end and having a terminal flange at its other end, a flanged riser section extending through said sleeve, an opposing pipe section also having a terminal flange adapted to register with the flange on the first mentioned pipe section, and means for sealing the joint between the flanges on said pipe sections when the same are in assembled relation, including a plurality of apertured plates, a plurality of bolt members each having a terminal lug member, the shanks of said bolts being adapted to be inserted through the apertures of said plates, retaining nuts adapted to be threaded on the ends of said bolts, and transversely 80 extending adjusting means carried by said terminal lug members of said bolt. 85

5. An anchorage unit for a heat exchange system, comprising a member having a terminal flange at one end, a riser pipe section having a terminal flange corresponding to the flange on said member and adapted when brought into tight engagement therewith to form a fluid-tight joint therewith, a centrally apertured plate carried by said pipe section, the aperture in said plate being of substantially smaller diameter than the extreme diameter of the terminal flanges, a sleeve of sufficient size to embrace said pipe section and being of inverted truncated-cone-like configuration at one end, and having a flange at its opposite end and means on said sleeve 90 for anchoring the same against rotation in a concrete base and clamp bolts carried by said plates and provided with adjusting screws in the heads thereof for securing said riser pipe section in fluid-tight engagement with the aforesaid co-operating flanged member. 95

6. An anchorage for a heat exchange system for buildings, comprising a sleeve, of inverted frusto-conical configuration adjacent one end adapted to receive a riser section, a pipe joint adapted to connect such riser section to a tubular member and means, including clamp bolts and adjusting screws carried thereby, which latter are adapted to cooperate with the aforesaid frusto-conical end of said sleeve for rigidly securing said pipe joint, while in position on such riser section and said tubular member, to said sleeve. 100

7. In an anchorage device for heat exchange systems in buildings, the combination comprising a sleeve adapted to be anchored in a floor of a building, and a pipe joint, including a plurality of centrally apertured plate members and clamp bolts therefor, said bolts being provided with supplemental retaining means extending transversely of the axis thereof for rigidly and 10 adjustably securing said pipe joint to said sleeve.

8. In an anchorage for a heat exchange system of a building, the combination comprising a cylindrical floor sleeve of variable 15 diameter immediately adjacent its upper end and of substantially uniform diameter throughout the major portion of its length, a pipe joint including clamp bolts carried thereby for retaining two flanged conduits 20 in intimate fluid-tight engagement with each other and means carried by said bolt members for rigidly securing said pipe joint to the upper end portion of said sleeve.

9. In an anchorage device for heat exchange systems in buildings, the combination comprising a sleeve adapted to be anchored in a floor of a building and a pipe joint, including a plurality of centrally apertured plate members adapted to encircle registering pipe sections and clamp bolts for said plate member, said bolts being provided with supplemental retaining means extending transversely of the axis thereof for rigidly 35 and adjustably securing said pipe joint to said sleeve, and said plate members having means for holding said supplemental retaining means in a predetermined alined position.

10. In an anchorage for a heat exchange 40 system of a building, the combination comprising a cylindrical floor sleeve of variable diameter immediately adjacent its upper end and of substantially uniform diameter throughout the major portion of its length, a 45 pipe joint including clamp bolts carried thereby for retaining two flanged conduits in intimate fluid-tight engagement with each other, means carried by said bolts for rigidly securing said pipe joint to said sleeve and 50 means for preventing rotation of said bolts while the pipe joint is being applied to a plurality of flanged conduits.

Signed at New York, in the city, county and State of New York, this 20th day of 55 March 1930.

DWIGHT D. KIMBALL.
